UNITED STATES PATENT OFFICE.

NILS M. LAGERGREN, OF PORTLAND, OREGON.

BED.

1,273,879.

Specification of Letters Patent. Patented July 30, 1918.

Application filed October 8, 1917. Serial No. 195,385.

To all whom it may concern:

Be it known that I, NILS M. LAGERGREN, a citizen of Sweden, residing at Portland, in the county of Multnomah and State of Oregon, have invented certain new and useful Improvements in Beds; and I do declare the following to be a full, clear, and exact description of the invention, such as will enable others skilled in the art to which it applies to make and use the same.

This invention relates to improvements in beds and more particularly to that type including an adjustable head rest.

The primary object of the invention is to provide a bed with a head rest which is adjustable to various angles and whose operating mechanism is easily operated and extremely simple in construction.

Another object is to provide a device of this character in which the mechanism for adjusting the head rest is protected by a casing, and which may be locked at various points, according to the desired angle of the head rest.

With these and numerous other objects in view my invention resides in the novel features of construction and in the combination and arrangement of the several parts as described in the specification and claim and clearly illustrated in the accompanying drawings which form a part of this application and in which;

Figure 1 represents a side elevation of my improved bed.

Fig. 2 is a horizontal sectional view taken on the line 2—2 of Fig. 1.

Fig. 3 is a longitudinally vertical sectional view of the bed on the line 3—3 of Fig. 2.

Fig. 4 is a top plan view of the bed.

Fig. 5 is a transverse vertical section on line 5—5 of Fig. 1, and

Fig. 6 is a detail perspective view of the shiftable section of the bed spring.

The preferred embodiment of my invention as illustrated in the accompanying drawings includes a bedstead comprising a head section H, a foot section F, and side rails R of any suitable construction.

Arranged adjacent the foot section and secured to and between the side rails R in any suitable manner is an U-shaped frame 1 formed from angle metal of inverted L-shape in transverse section, said frame having its closed end disposed adjacent the foot section F and having its parallel side

arms 2 terminating at points approximately midway the length of the side rails. For the purpose of providing space for pivotal connection and movement of a head rest to be described, a portion of the horizontal flange at the end of each arm is cut away and the vertical flange below the cut-away portion is provided with an aperture 3 whose purpose will be seen as the description progresses. The horizontal flange from each cut-away portion to points spaced from said cut-away portions are bent downwardly as indicated at 4 for a purpose to be set forth.

Disposed at the head of the bed is an U-shaped frame 5 forming a head rest, said frame being formed from angle metal of inverted L-shape in transverse section. The vertical flanges of the parallel arms 7 are provided adjacent their outer ends with apertures adapted to align with apertures 3 and with apertures in the side rails R, said frames and side rails being connected together by bolts or the like 6 which extend through the aligned apertures and pivotally connect the frame 2 to the bedstead and to the relatively stationary frame 1, the head rest being movable about the bolts 6, each of which serves as a pivot. In forming the frame 5 I employ a length of angle metal of inverted L-shape in transverse section, the end sections or arms being bent at right angles to the central section 8 and when in position the ends of the horizontal flange forming the central section 8 are disposed above the adjacent ends of the horizontal flanges on the end sections or arms 7, the overlapping ends being provided with aligned apertures through which rivets or the like fastening elements 9 pass to retain the sections in proper relative position. The horizontal flange of each arm 7 is slit transversely at a point adjacent the inner edge of the horizontal flange of the central section 8. The slits extend substantially one-half the width of the flanges, and the metal from said slits to the farther ends of the flanges is bent downwardly at right angles to form additional flanges to coact with the vertical flanges of the angle metal in forming guideways 10 whose purpose will be hereinafter set forth.

The two frames 1 and 5 are covered with a single strip of wire mesh fabric 11 which is secured at its ends to the closed ends of the frames and has its sides secured to the parallel arms 7 of the head rest frame 5.

and to those of the horizontal flanges of the arms 2, to the points where the latter flanges are bent downwardly, from which points to the pivotally connected ends of the arms, 5 the edges of the fabric are left unattached, so that when the fabric between the unattached points will yield to a greater extent than the remaining fabric and will thus provide for comfortably conforming to the 10 body of a person supported by the bed in a sitting position or in the reclining posture suggested by the position of the frame 5, in Fig. 3.

For the purpose of raising the head rest 15 to the desired angle, a pair of curved levers 12 are pivotally connected intermediate their lengths to the side rails R, each lever having an anti-friction roller or shoe 13 on its upper end to be received in the adjacent 20 guideway 10 on the head rest, and having in its other end an aperture for a purpose to be seen as the description progresses.

For the purpose of operating the levers 12 and thereby adjusting the head rest, a 25 windlass 14 is mounted on the outside of the foot section F, being vertically disposed and comprising a shaft 15 having its upper and lower ends mounted in bearings 16, the lower bearing being formed in the end of 30 a casing tube 17 which incloses the shaft and is brazed or otherwise suitably secured to the cross bars of said foot section. The upper bearing for the shaft 15 is formed in a flat cap plate 18 which closes the upper 35 end of the casing 17 and is of a diameter greater than that of the casing.

The cap plate 18 also provides an additional means of connection between the casing 17 and the foot section F, in that a portion 40 of the flange overlaps the top cross-bar of said section and has laterally oppositely directed ears 19 which are brazed to said cross-bar. The upper end of the shaft extends slightly above the cap plate 18 and has 45 non-rotatably mounted thereon an operating crank 20 and between said crank and plate a ratchet wheel or pinion 21 is mounted and adapted to be engaged by a pawl 22 which is pivoted at one end to one of the attaching 50 ears 19.

At a point near its lower end the casing 17 is slit vertically and has horizontal slits intersecting the upper and lower ends of the vertical slit, the metal on each side of the 55 vertical slit being bent laterally outward to

form spaced flanges 23 between which pass a set of cables to be hereinafter described. In order that the levers 12 may be operated, a cable 24 is connected substantially midway its length to the vertical shaft 15 and 60 has its ends passed over suitable pulleys or sheaves 25 mounted on the corner posts of the head section H and then brought back and connected to the apertured lower ends of the levers 12. 65

In raising the head rest the crank is preferably turned clock-wise, thereby winding the cable upon the shaft, and transmitting motion to the levers; and, when the head rest is to be lowered, the crank is turned 70 counter-clockwise to wind on the shaft, in an opposite direction to that of the cable 24, a cable 24' which has one end connected to the shaft and its other end passed over a pulley 26 mounted on the head section substantially midway between the corner posts and connected to the closed end of the head rest. 75

From the foregoing description of the construction and operation of my improved 80 bed, the operation thereof, will be readily understood, but it is also to be understood that numerous changes in the minor details of construction may be made without sacrificing the principal advantages. 85

I claim:

A bed having head and foot sections and an adjustable head rest; in combination with means for operating said rest including a vertical windlass and cables wound thereon 90 and a vertical casing for said windlass formed of a single length of tube having bearings for said windlass and mounted on the foot section, the lower end portion of said casing having a vertical slit and a pair 95 of horizontal slits intersecting the upper and lower ends of said vertical slit, the metal on the opposite sides of said vertical slit being bent laterally outward to form spaced flanges between which said cables pass, 100 an operating crank on the upper end of said windlass and a pawl and ratchet mechanism therefor.

In testimony whereof I have hereunto set my hand in the presence of two subscribing 105 witnesses.

NIILS M. LAGERGREN.
